ELECTROMAGNETIC PULLEY

Dan E. Koerner, East Troy, Wis., assignor to
Dings Magnetic Separator Co., Milwaukee, Wis.,
a corporation of Wisconsin

Application April 3, 1953, Serial No. 346,617

3 Claims. (Cl. 209—219)

1

The present invention relates generally to improvements in the art of magnetically separating normally mixed magnetic and non-magnetic materials, and relates more specifically to improvements in the construction and operation of electrically energized magnetic pulleys or drums for removing magnetic substances from non-magnetic bulk material which is ordinarily subjected to magnetic influence at the pulley or drum periphery.

The primary object of my invention is to provide an improved magnetic pulley or drum which is electrically energized in a manner whereby maximum efficiency in separation of mixed magnetic and non-magnetic materials applied to the pulley or drum periphery results.

It is common practice to utilize a so-called magnetic pulley or drum type separator for the purpose of removing magnetic substances from primarily non-magnetic bulk material which is transported in the form of a layer over the periphery of the revolving pulley or drum. In some of these magnetic separators, the magnets for effecting the separation are of the permanently magnetized type, while in others these magnets are electrically energized, but in either type the bulk mixture of non-magnetic material and magnetic substances is usually conveyed over the pulley periphery by means of a non-magnetic belt. Heretofore each electrically energized magnetic pulley has been composed of several annular magnets each having a pair of positive and negative poles spaced apart axially of the pulley and adapted to be energized by a coil or winding confined between the spaced poles, and the adjoining poles of the successive magnets were of alternate or opposite polarity. In wide pulleys embodying four of these annular magnets, there were four coils and five successive poles the inner three of which each consisted of the positive pole of one magnet adjoining the negative pole of the next adjacent magnet, thus creating a relatively weak magnetic field at the center of the pulley face where the strongest field is in fact desired.

The belts for conducting the mixed bulk material toward these magnetic separating pulleys are necessarily more heavily loaded at the center and are frequently troughed in order to prevent spillage of material from the opposite sides thereof, but in any event, the layer of material passing over each pulley periphery remains considerably thicker at the center of the conveyor belt than along the edges, so that in order to insure most efficient removal of magnetic substances the magnetic field should be most intense and of greatest

2

effective range near the center of the advancing stream. With the prior electromagnetic separating pulleys this was not the case especially in four magnet assemblages, so that maximum removal of magnetic substances embedded within the central thicker portions of the advancing mass could not be assured due to the substantial uniformity or even weaker field at the center of the pulley face, and the neutralization of some flux lines remote from the pulley periphery.

It is therefore an important object of the present invention to provide an improved electromagnetic pulley of the above type, wherein the magnetic field is of maximum intensity and most effective range at the medial portion of the pulley periphery so that the thickest portion of the mass of material being transported over the pulley periphery will be subjected to most effective removal of magnetic substances throughout its entire extent.

Another important object of this invention is to provide a magnetic pulley composed of several adjoining revolving magnets which are electrically energized in a manner whereby the magnetic lines of force are utilized to the utmost extent in removing magnetic substances from bulk non-magnetic material passing through the magnetic field.

A further important object of the invention is to provide an improved electrically energized magnetic separating pulley cooperating with a longitudinally troughed or with a flat feed belt for conducting a centrally thickened continuous layer or stream of bulk material over the pulley periphery, and wherein the magnetic field has greatest intensity and most effective range at the thickest portion of the stream and gradually diminishes toward the opposite edges thereof.

Still another important object of my invention is to provide an improved electromagnetic separating drum or pulley of simple, compact and durable construction and adapted to most effectively remove magnetic substances from bulk material subjected to the magnetic field created along the pulley periphery.

These and other more specific objects and advantages of the present invention will be apparent from the following description, from which it will be apparent that the gist of the improvement is the provision of an electrically energized magnetic pulley especially cooperable with a bulk material feed belt for transporting a medially thickened stream, and wherein several adjoining magnets having laterally widened annular peripheral pole shoes which are rotatable

about the pulley axis and are energized so as to create a magnetic field extending along the pulley periphery and having maximum intensity at the central plane perpendicular to said axis.

A clear conception of the features constituting the present improvement, and of the construction and operation of several typical embodiments of the invention, may be had by referring to the drawing accompanying and forming a part of this specification wherein like reference characters designate the same or similar parts in the various views.

Fig. 1 is a part sectional elevation of a typical quadruple magnet electromagnetic pulley, the section having been taken along the irregular line 1—1 of Fig. 2;

Fig. 2 is a part sectional end view of the magnetic pulley shown in Fig. 1, the section having been taken along the line 2—2;

Fig. 3 is a side view of a magnetic separating installation embodying one of the improved electromagnetic pulleys cooperating with a troughed feed belt, and showing the installation in action;

Fig. 4 is a diagrammatic central longitudinal section through the upper half of a quadruple magnet pulley such as shown in Figs. 1 and 2, showing the relative disposition of the magnets and the magnetic field acting upon the layer of bulk material; and

Fig. 5 is a diagram similar to that of Fig. 4 but depicting a dual magnet pulley embodying a modification of the invention.

While the invention has been illustrated and described herein as being especially applicable to magnetic separating drums or pulleys cooperating with troughed feed belts, it is not the intent to unnecessarily restrict the invention to such installations; and it is also contemplated that specific descriptive terms employed herein be given the broadest possible interpretation consistent with the disclosure.

Referring to Figs. 1 to 4 inclusive of the drawing, the quadruple electrically energized magnetic pulley shown therein, comprises in general, a main shaft 7 having a series of four annular magnets 8 mounted thereon each of which is provided with a pair of poles 9, 10 separated by an annular space and which may have annular magnetic pole shoes 11 secured thereto; an electric energizing coil or winding 12 confined within the annular space of each magnet 8; and a series of non-magnetic coil cover rings 13 interposed between the successive pole shoes 11 and 11 and cooperating with these shoes 11 and with non-magnetic end rings 14 to provide a slightly crowned or flat annular pulley face.

The annular magnets 8 and their poles 9, 10 are formed of magnetically permeable material and of similar construction, each being provided with a central hub 15 connected thereto by radial arms 16 and which are firmly secured to the shaft 7 by means of keys 17. The corresponding arms 16 of all of the magnets 8 are united by tie-bolts 18 which clamp the adjoining poles 9, 10 of the successive magnets snugly against each other. The annular pole shoes 11 preferably extend laterally over the peripheries of the adjacent coils 12 and are also formed of magnetic material, being rigidly attached as by welding, to the peripheries of the adjacent annular poles 9, 10; and the non-magnetic cover and end rings 13, 14 may also be rigidly secured to the adjacent magnet poles 9, 10 and pole shoes 11, in any suitable manner, as by welding.

The annular coils or magnet energizing wind-

ings 12 are surrounded by protective bands 20 and are confined within the spaces between the magnet poles 9, 10; and these coils 12 are adapted to be energized from any suitable source of direct current through conductors passing through moisture proof conduits 21. These conduits 21 communicate with a central duct 22 formed in the shaft 7 through a sealed tubular coupling 23, and the energization of the windings 12 must be such as to cause all of the poles 9 to be of like as indicated by the letter N while the poles 10 must be of opposite polarity as indicated by the letter S, in Fig. 4.

The improved magnetic pulley may be installed in a typical separating plant such as illustrated in Fig. 3, wherein the main shaft 7 is mounted in bearings 25 carried by inclined beams 26, and a non-magnetic conveyor belt 27 for bulk material 28 the major portion of which is composed of non-magnetic substance, but which may contain magnetic articles or substances 29, coacts with the periphery of the pulley. The material feeding belt 27 preferably has its upper inclined stretch 30 troughed in advance of the magnetic pulley by means of relatively inclined idler rolls 31 journaled on brackets 32 also carried by the beams 26 and a member 33 for segregating the removed magnetic substances 29 from the bulk material 28 is located beneath the magnetic pulley below the separating zone 34. The untreated bulk material may be deposited within the trough shaped upper belt stretch 30 from any suitable source, and the separating pulley may be continuously rotated in a clockwise direction as viewed in Fig. 3 either by the belt 27 or by power applied directly to the shaft 7, while the magnet windings 12 may be energized from any convenient source of direct current through conductors and a commutator in a well known manner, to create magnetic fields 35 as depicted in Fig. 4.

When the improved quadruple magnetic pulley has been properly constructed and assembled as described, and installed as illustrated in Fig. 3, the two flux fields 35 extending entirely around the pulley periphery will have greatest magnetic intensity at the center of the pulley and will also have considerable magnetic range between the pulley center and its opposite ends, because the adjoining positive poles 9 will concentrate the flux at the central pole shoe 11, while the coacting positive and negative poles 9, 10 located between the pulley center and its opposite ends will neutralize each other. As the upper conveyor belt stretch 30 feeds the bulk material 28 toward the separating zone 34, the trough shape thereof produced by the rolls 31 will permit the loose substance to be deposited in the form of a rather thick layer without having the material spill over the belt edges.

After leaving the rolls 31, the upper belt stretch 30 flattens out and causes the upwardly advancing stream of material 28 to assume greater thickness along its mid-portion and to taper off toward its opposite sides as shown in Fig. 4, and when the layer of material passes through the separating zone 34 directly above the magnetic pulley the magnetic substances 29 will be attracted toward the pulley axis and will cling to the advancing belt 27 while the non-magnetic substance 28 will cascade and drop by gravity beyond the segregating member 33. As the lower run of the belt 27 advances downwardly away from the pulley periphery, it gradually pulls the magnetic substances 29 out of the fields of mag-

netic influence whereupon these substances drop by gravity beyond the left inclined side of the member 33. Because of the formation and relative disposition of the magnets so as to produce magnetic fields of great range and of maximum intensity at the center of the medially thickened stream of material, most efficient extraction and removal of the magnetic substances 29 is made possible.

While the quadruple magnetic pulley of Figs. 1 to 4 inclusive has proven highly satisfactory and far more efficient than the prior electromagnetic separating pulleys of this general type, in actual commercial use, similar improved results are also obtainable with a modified dual magnet pulley such as illustrated diagrammatically in Fig. 5. In the modified assemblage only two magnets 8' each energized by a direct current electric winding 12' and having opposite poles 9, 10 cooperating with annular pole shoes 11, are provided, but the gaps between the successive pole shoes 11 have rings 11' of magnetic material disposed therein and surrounding the adjacent coils 12'.

This modified pulley may also be installed as shown in Fig. 3, and during normal operation thereof, the magnetic rings 11' provide a central zone and function to pull the inner lines of force of the magnetic fields 35' toward the portions of the advancing conveyor belt 27 located between its center and opposite side edges. The fields 35' created with this modified assembly also have great magnetic range, with maximum flux intensity along the central plane of the stream of material 28, thereby also insuring most effective removal of magnetic substances 29 especially from centrally thickened layers of the bulk substance.

From the foregoing detailed description it will be apparent that the present invention provides an electro-magnetic separating pulley wherein the magnetic field distribution is radically different and far superior to pulleys of this general type as heretofore constructed with the adjacent poles 9, 10 always of opposite polarity. In both 40 of the improved magnetic pulleys shown, the adjoining poles 9 of the adjacent magnets 8 at the center of the pulley periphery have positive polarity, while the poles 10 at the opposite ends of the pulley have negative polarity, thus producing magnetic fields of considerable range and of maximum intensity at the thickest central portion of the stream of bulk material 28. Actual 50 tests of the improved electromagnetic pulleys have shown that a pulley having a diameter of thirty inches has a field of greater magnetic depth than a standard forty eight inch diameter as previously constructed, and the improvement may be readily incorporated in any electromagnetic pulley or drum wherein the layer of material 28 being treated is of greatest thickness at the center of the stream.

In the prior magnetic pulleys of the type herein described, the magnetic lines of force remote from the pulley face tended to neutralize 65 each other thus losing the advantages thereof, whereas the present invention obviates this loss. It should also be noted that the use of separate pole shoes 11 coacting with the poles 9, 10 augment the proper distribution of the burden 70

over the conveyor belt 30, and that the bulk material may be fed upon the pulley or drum periphery without the use of a conveyor belt, in a manner well known in the art. It is also to be noted that the center poles 9 of the assemblage may be of either positive or negative polarity, depending upon the manner in which the coils 12 are energized.

It should be understood that it is not desired to limit this invention to the exact details of construction of the magnetic pulleys herein shown and described, since various modifications within the scope of the appended claims may occur to persons skilled in the art.

I claim:

1. In an electromagnetic separating pulley, a pair of coaxial and adjoining electromagnets each having annular poles of opposite polarity separated by an annular outwardly open space, an annular direct current energizing winding for each of said magnets confined within its said space, and an annular magnetic pole shoe surrounding each of said magnet poles and extending laterally partially over the adjacent space and over the periphery of the adjacent winding, the adjoining annular poles of the two adjacent magnets having positive polarity and the other annular magnet poles having negative polarity.

2. In an electromagnetic separating pulley, a pair of coaxial and adjoining electromagnets each having annular poles of opposite polarity separated by an annular outwardly open space, an annular direct current energizing winding for each of said magnets confined within its said space, an annular magnetic pole shoe surrounding each of said magnet poles and extending laterally partially over the adjacent space and over the periphery of the adjacent winding, the adjoining annular poles of the two adjacent magnets having positive polarity and a non-magnetic ring spanning the gap between adjacent pole shoes and coacting therewith to provide a continuous pulley periphery.

3. In an electromagnetic separating pulley, two coaxial and adjoining electromagnets each having a pair of axially spaced annular poles extending outwardly away from the common axis thereof, an annular direct current energizing winding for each of said magnets confined within the space between its said poles, an annular magnetic pole shoe secured to the periphery of each of said magnet poles and projecting to a predetermined extent laterally away from its carrying pole partially over the adjacent space and over the periphery of the adjacent winding, and a non-magnetic ring spanning the gap between adjacent pole shoes and coacting therewith to provide a continuous smooth pulley periphery.
